UNITED STATES PATENT OFFICE.

ADOLPH F. ANDERSON, OF CHICAGO, ILLINOIS, ASSIGNOR TO APEX APPLIANCE COMPANY, OF CHICAGO, ILLINOIS, A CORPORATION OF ILLINOIS.

POWER-TRANSMITTING MECHANISM.

1,405,382.

Specification of Letters Patent.

Patented Feb. 7, 1922.

Application filed November 7, 1919. Serial No. 336,363.

To all whom it may concern:

Be it known that I, ADOLPH F. ANDERSON, a citizen of the United States, residing at Chicago, in the county of Cook and State of Illinois, have invented certain new and useful Improvements in Power-Transmitting Mechanism, of which the following is a specification.

This invention relates to power transmitting mechanism.

It is particularly applicable for operating power driven washing machines.

One of the objects of the invention is to provide an improved power transmitting mechanism.

Another object is to provide improved operating mechanism for a washing machine.

Another object is to provide an improved support for carrying power transmitting mechanism.

Another object is to provide a compact, simple and efficient power transmitting mechanism.

Other objects and advantages will appear from the specification and claims.

An embodiment of the invention applied to a washing machine is illustrated in the accompanying drawings, wherein—

Fig. 1 is a longitudinal section of a washing machine showing the power transmitting mechanism in end elevation.

Fig. 2 is a longitudinal section through the mechanism.

Fig. 3 is a top plan thereof.

Fig. 4 is a section on the line 4—4 of Fig. 3, and

Fig. 5 is a perspective of the base of the transmitting mechanism.

The washing machine shown comprises in general an oscillatingly mounted tub 5 and a wringer 6, both of which are operated by the power transmitting mechanism. The tub and transmitting mechanism are completely enclosed by a housing 7.

One form of housing is described in detail and claimed in my copending application, Serial No. 336,362 executed of even date herewith. In general this housing comprises a pair of rigid end walls between which the tub is pivotally mounted. The side walls consist of two slidably opening sides 8 and 9 whereby the lower part is closed or opened for access to the bottom of the tub and the power transmitting mechanism. The top of the housing is provided with a slidably

mounted cover 10 whereby access may be had to the opening in the top of the tub. The housing is carried on a base formed of four angle bars 11, secured together at their ends to form a substantially rectangular frame.

Extending between and mounted upon the front and rear angle bars 11 is a base 15 which is self contained and which carries the power transmitting mechanism unit. The base and mechanism with the motor is bodily removable from the casing.

Base 15 carries an electric motor 16, which furnishes the power for driving the tub and wringer, and a train of gears whereby the power is transmitted from the motor to the tub and wringer. The gear train has a pulley 17 which is connected to the pulley of the motor by a belt 18.

Pulley 17 is rigidly secured to a shaft 19 to which is also rigidly secured a pair of pinions 20 and 21. Pinion 20 meshes with a gear wheel 22 rigidly secured to a shaft 23. Shaft 23 is provided with a bevel pinion 24 which meshes with a bevel pinion 25 on a vertical shaft 26. Shaft 26 drives the wringer rolls.

Pinion 21 meshes with a gear wheel 30 carried by a shaft 31. A connecting rod 32 pivotally connected at one end to gear wheel 30 is operatively associated at its upper end with the tub, so that the tub may be oscillated thereby when gear wheel 30 is rotated by the motor.

Suitable clutch and controlling apparatus may be associated with the tub and connecting rod whereby the tub is oscillated and its operation may be suitably controlled. One form of such apparatus is disclosed and claimed in my copending application, Serial No. 336,283 executed on even date herewith.

Base 15 may be formed of a single casting, as most clearly shown in Fig. 5. It comprises an open frame work having angle shaped sides 35 and 36 which are substantially parallel throughout the greater portion of their length. Sides 35 and 36 are interconnected at their ends by angle shaped end pieces 37 and 38. The end pieces are provided with inturned flanges 40 and 41 which rest upon and are bolted to the horizontally extending flanges of end angle bars 11, as clearly shown in Fig. 2.

The base is provided with three inboard

bearings 42, 43 and 44 for journaling shafts 31, 19 and 28, respectively. These bearings are made long enough so that the shafts do not require any other support. Bearing 44 is provided with a lug 45 which furnishes a bearing for shaft 26.

The forward end of base 15 has a pair of overturned flanges 46 and 47, which provide guideways for the motor bed 48. The motor bed may be moved along the guideways by 10 an adjusting screw 49 to regulate the tension in belt 18.

Having described my invention, what I claim is:

- 15 1. A power transmitting mechanism unit for driving a washing machine, having in combination an elongated base plate provided at one end with inturned guideways; a sliding, motor-supporting longitudinally 20 adjustable plate within the guideways; a motor mounted on said sliding plate; three parallel transversely positioned inboard journal bearings arranged longitudinally in spaced relation on said base plate; a shaft supported in each said bearing; gearing connecting the shafts and means for connecting the motor to the gearing.

2. A power transmitting mechanism unit, for driving a washing machine, having in combination a base plate provided with two substantially parallel side members connected at their ends; a plurality of inboard, spaced apart, parallel bearings mounted on and connecting the side members; guideways extending longitudinally of the base; a 30 motor supporting plate between the guide members and means to adjustably move the plate to and from the bearings.

3. An integral one piece base plate for supporting a power transmitting mechanism 40 unit, for driving a washing machine, having in combination two side members connected together at their ends and diverging at one end to provide a motor support; parallel guide ways on the wider end to receive a longitudinally adjustable motor supporting plate; and a plurality of spaced 45 apart bearing hubs connecting the side members together between the ends of the structure.

In testimony whereof I hereunto subscribe my name.

ADOLPH F. ANDERSON.
